[57] CLAIM

The ornamental design for a hood ornament as shown and described.

DESCRIPTION

FIG. 1 is a front perspective view of a hood ornament showing my new design;

FIG. 2 is a rear elevation view thereof;

FIG. 3 is a right side elevation view thereof; and

FIGS. 4, 5, and 6 are sectional views taken along the lines 4—4, 5—5, and 6—6, respectively, in FIG. 2.

The bottom of the hood ornament is planar and unornamented.
